UNITED STATES PATENT OFFICE.

WILEY J. HUDDLE, OF CHICAGO, ILLINOIS.

CABINET DISHWASHER.

Application filed June 13, 1921. Serial No. 477,249.

This invention relates to machines for washing dishes, and more particularly to machines of this kind which are adapted to be used in an ordinary kitchen.

Generally stated, the object of the invention is to provide an inexpensive and practical form of machine which can be used not only for washing the dishes, but which will also serve very much like an ordinary cabinet or cupboard for storing the dishes, so that after washing and drying the dishes they can be allowed to remain in the cabinet from which they are selectively removable from the front thereof, just as they would be removed from an ordinary pantry or kitchen cupboard.

It is also an object to provide certain details and features of construction and novel combinations tending to increase the general efficiency and the desirability of a combined dish washing machine and storage cabinet or cupboard of this particular character.

To these and other useful ends, the invention consists in matters hereinafter set forth and claimed and shown in the accompanying drawings in which—

Figure 1 is a perspective of a dish washing machine embodying the principles of the invention, showing the same installed in conjunction with an ordinary kitchen sink.

Figure 2 is an enlarged front elevation of said machine.

Figure 3 is a vertical section on line 3—3 in Figure 2, showing certain parts (in dotted lines) in the positions which they occupy while the cabinet is being filled or while the dishes are being removed therefrom.

Figure 4 is a detail longitudinal section on line 4—4 in Figure 3, showing certain portions broken away for convenience of illustration.

Figure 5 is a detail section on line 5—5 in Figure 4.

Figure 6 is an end elevation of the said machine.

Figure 7 is a similar view of the other end of said machine.

As thus illustrated, the invention comprises a boxlike structure having a back wall 1, a top wall 2, a bottom wall 3 and end walls 4 and 5 of sheet metal or any other suitable or desired material. The front of the cabinet thus provided is equipped with a door 6 which, with the front wall 7, forms

the entire flat front of the structure. It will also be seen that the top of this door, in conjunction with the said top wall 2, forms the flat top of the cabinet. The ends of said door have inclined edges 8 which meet the inclined edges 9 of the end walls 4 and 5, whereby the door 6 comprises not only a portion of the front of the cabinet, and a portion of the top of the cabinet, but also a portion of each end of the cabinet. The top of said door is connected by hinges 10 with the top wall 2, so that said door can be raised and swung upward and over on top of the cabinet, as shown in dotted lines in Figure 3, when the cabinet is to be filled or when the dishes and other table articles are to be removed therefrom.

The bottom of the cabinet has a dish water reservoir 11, and a longitudinal shaft 12 extends above this reservoir, said shaft being provided with blades 13 to splash the water held in said reservoir. Thus the cabinet forms a splash chamber above the dish water reservoir, with the front opening of the cabinet above the water line. A fan 14 is also mounted on said shaft in position to blow air through the cabinet after the dishes are washed, and after the water is drained off, thereby to dry the dishes. Preferably the shaft 12 is driven by a motor 15 through the medium of a belt 16 and the pulley wheel 17 on the outer end of the shaft.

A rack 18 is removably mounted in the base portion of the cabinet, in front of and over the shaft 12, so that the front portion 19 of this rack is adapted to hold knives and forks and spoons, while a shelf 20 is provided for the plates or other large articles, as shown, with arched portions 21 to space the plates apart and hold them upright in vertical planes. It will be understood that this rack 18 can be constructed from wire, or any suitable materials, so that it will form a sort of basket to not only hold the articles to be washed, but to permit free entrance of the water thrown from the reservoir by the blades 13 previously mentioned.

Another rack or basket 22 is hinged at 10 and formed with upper and lower shelves 23 and 24 to support cups and saucers and glasses or similar articles. This rack or basket 22 is open at its front, so that the articles can be easily placed therein and removed therefrom. When the cover or door 11

6 is open, the rack or basket or cagelike supporting means 22 can be raised and swung upward and over to temporarily rest in the door 6, thereby affording access to the space in rear of this rack.

5 A burner 25, of any suitable character, but preferably adapted to burn gas, is arranged below the bottom 3 as shown, to heat the water to a temperature suitable for 10 washing the dishes. Said burner is connected to the gas supply pipe 26 by means of a valve 27 provided with a handle 28, and a small pipe 29 leads from the pipe 26 to a point over the burner 25 to provide a pilot 15 light when the gas is turned on.

The water reservoir has a drain pipe 30 at one end thereof, and the hollow device 31 is movable up and down in a guide 32 above the opening of said drain pipe, thereby to 20 open and close the drain, a rock shaft 33 provided with a handle 34 being provided for this purpose. When the handle is swung forward the device 31 is raised to open the drain pipe 30, and when the handle is swung 25 backward said device is lowered to close said opening. However, inasmuch as the device 31 is open at the top thereof, an overflow outlet is always provided to take care of the surplus in case the water is allowed to enter 30 the reservoir after it is filled to the proper level. The water can be supplied to the machine in any suitable or desired manner. As shown, the machine is installed at the left of an ordinary kitchen sink 35, and a 35 water pipe or connection 36 connects the machine with the plumbing of the sink. The drain pipe 30 empties into the sink, and the latter forms practically a part of the dish washing apparatus thus provided. To 40 prevent the gas from being turned on until after the drain 30 is closed, so that water will always be in the reservoir while the heater is in operation, the plate 37 of the handle 34 is provided with a notch 38 which 45 engages the upper end of the handle 28, thereby preventing the operation of the latter except when the notch 38 is opposite said upper end portion 39 of the handle, as shown in Figure 6, as with the parts in these positions the handle 28 can be raised to turn on 50 the gas. The operator will close the drain, turn on the water, and then turn on the gas to heat the water. All this does not interfere with the ordinary use of the sink, as 55 the washer is at one end thereof, and not above the sink, whereby the dishes can first be partially washed in the sink and then put in the combined washer and dryer and storage cabinet.

60 For the admission of air to the cabinet, while it is still in heated condition, to dry the dishes, and for the discharge of the air therefrom, the ends of the cabinet are preferably provided with openings 40 at suitable 65 points above the water line. This provision

is obviously useful in drying the dishes, after they are washed, without taking them out.

The cover or door 6 must close tightly, of course, to prevent the water from escaping 70 from the cabinet during the washing operation, and for this purpose a catch 41 is provided, of any suitable character, at the lower edge of the door or closure, to engage a lug 75 42 on the front of the cabinet.

Brackets 43, or any suitable means, can be employed for supporting the cabinet in elevated position on the wall, at such a height that it will serve conveniently as a storage cabinet or wall cupboard for the dishes, like 80 an ordinary cupboard, as well as a washing machine. This also, of course, affords ample clearance below the machine for the operating motor 15 previously mentioned, being 85 on the bottom of the cabinet. Thus the invention not only contemplates a cabinetlike washer in which the dishes may be left after the washing operation is completed, and after the dishes are cleaned while still heated, of course, but also contemplates a 90 dish washer which is designed and intended to be used, in a satisfactory and convenient manner, as an ordinary storage cabinet or wall cupboard, thereby dispensing with or 95 obviating the necessity of any removal of the dishes after they are washed and dried, and thus reducing the work. The upper rack or cage forms the means for affording access to the lower rack or basket, and must be swung up for this purpose, and both 100 baskets must be displaced to permit access to the washing means. The holding means in the cabinet keep the dishes separate, allow them to drain themselves dry, and afford selective or individual removal of the dishes 105 or other articles, in the sense that they can be removed one by one, when needed for the table, just as they would be removed from the shelves of an ordinary pantry or kitchen cupboard, for there is a place for each dish. 110

Thus, with the foregoing construction, the washing machine which is also a storage cabinet has a front opening above the water line of the dish water reservoir, so that the splash chamber in which the dishes are not 115 only washed but also stored is entirely above the washing means, and is accessible at the front thereof for the insertion and removal of the dishes and other table articles. A moderate amount of dish water in the reservoir will be sufficient for the purpose, as it can be heated and maintained at the desired temperature during the washing operation, so that no water is wasted. The washing dish water can be discharged, after the dishes are washed, and the reservoir can then be filled with rinsing water, very obviously, and at no time can the heat be turned on while the drain from the dish water reservoir is open. In other words, to turn 125 130

on the heat, it is necessary to also close the drain, which makes the washer and cabinet a practical and safe thing to place in the hands of the average person. Furthermore, no expensive plumbing is necessary for the installation of the washer and cabinet shown and described, for the plumbing of the sink serves also as the means for draining off the water from the washing machine after the dishes are washed, and after the dish water has been discharged into the sink.

It will be seen that the machine is of the splash system type, in which the dish water or splash water is splashed upward upon the dishes. The cabinet is adapted to receive fresh air, as explained, to dry the dishes, thus obviating the necessity of taking out and wiping the dishes, the drying thereof in the manner described being sufficient to permit the dishes to remain in the cabinet, without taking them out and wiping them, until they are again needed for service. The top wall 2 is fixed or permanent, of course, being rigid, with the back wall 1 and the end walls 4, and hence the splash chamber above the splasher is tight all around and cannot leak and the water splashed up upon this wall 2 drips back again on to the dishes, and from the latter into the reservoir which holds the splash water. The burner which heats the splash water is supported by the bottom of the cabinet, and

the drying and storage chamber is thus heated also, in the manner explained.

What I claim as my invention is:—

1. In a dish washing machine, a reservoir for water to be splashed onto the dishes, a rotary shaft extending horizontally above the bottom of said reservoir, splash means mounted on said shaft, ventilating means comprising end walls having openings therein at opposite ends of said reservoir, forming a closed splash chamber into which the air can enter through one opening and leave through the other opening, thereby to dry the dishes and the interior of the machine after the dishes have been washed, means on said shaft to draw the air into the machine, and means for rotating said shaft, said machine having means to support the dishes in position for washing and drying, and for the storage thereof.

2. In a dish washing machine and storage cabinet for dishes or other table articles, a front door therefor, a supporting rack for the dishes or other table articles, and means for hinging said rack to swing outward and upward and over the top of the cabinet.

3. A structure as specified in claim 2, said door being also hinged to swing upward and onto the cabinet, and being formed to receive said rack.

WILEY J. HUDDLE.
